UNITED STATES PATENT OFFICE.

EVEN J. ROHNE, OF MINNEAPOLIS, MINNESOTA.

THERMOSTAT.

1,323,203.

Specification of Letters Patent.

Patented Nov. 25, 1919.

Application filed February 28, 1918. Serial No. 219,718.

To all whom it may concern:

Be it known that I, EVEN J. ROHNE, a citizen of the United States, and a resident of Minneapolis, in the county of Hennepin and State of Minnesota, have invented certain new and useful Improvements in Thermostats, of which the following is a specification.

One object of my invention is to provide, 10 in a simple, inexpensive type of thermostat, an element so mounted that it will not readily lose its adjustment.

Another object of my invention is to provide, 15 in a thermostat, simplified means for protecting the thermostatic element.

Another object of my invention is to provide, 20 in a thermostat, a simplified means of adjustment.

With these and incidental objects in view 25 the invention consists of certain novel features of construction and combination of parts, the essential elements of which are hereinafter described with reference to the drawing which accompanies and forms a part of this specification.

In the drawing Figure 1 is a plan view of my improved thermostat with a portion of the adjusting dial broken away, and Fig. 2 is a side elevation of the same.

30 As shown in the drawing, the mounting plate 1 has extending therefrom, and formed back over the top thereof, a tongue 2.

Ears 3 and 4, formed from the base plate 1, clamp the tongue 2 between the locating 35 ears 5 and 6 and hold in place the thermostatic element 7 composed of dissimilar metals clamped between the two pieces of the insulation 8 and 9.

In assembling the insulation and thermostatic element, I prefer to exert sufficient 40 pressure on the top of the tongue 2 so as to embed the thermostatic element in the insulation, thereby obviating any possibility of side motion of the thermostatic element.

45 The wire 10, either soldered to, or connected by pressure only, with the element 7, is brought out for forming one side of the circuit, the base plate forming the other side, and with the ears 3 and 4 forced strongly 50 down, the thermostat is so solidly held that the set of the base plate and the element is permanent.

Looking at Fig. 2, it will be seen that the 55 tongue 2 is carried forwardly beyond the ears 5 and 6, forming an adjustment means 11.

The end 12 of the base plate is formed

upwardly to serve as a stop for the extension 11, and the dial 13, carrying a screw 14 threaded in the extension 11 and rotatably 60 carried at 15 in the base plate, provides means for adjusting the extension 11 with respect to the base plate.

A contact point 16, carried by the extension 11, and a contact anvil 17 carried by the 65 thermostat element 7, is hence adjustable by means of the dial 13, and the temperature at which the contact between the point 16 and the anvil 17 will open or close will be determined by the position of the dial 13.

70 A rib 18, formed in the base plate from the point 19 and around on the tongue 2 to the point 20, stiffens the structure, and apertures 21 are provided for mounting the base plate to an electric pad or any other device 75 with which it is to be employed.

The foregoing description, together with the drawing, will readily show that while the structure I have provided is exceedingly 80 simple and inexpensive to manufacture, it is, at the same time, rigid and permanent with regard to the fixing of the thermostat element, while, at the same time, the point at which the thermostat contact will open or close may be adjusted by simplified means. 85

In order to reduce the wear on the extension 11 and dial 13, I prefer to carry on the screw 14 a brass washer 22, although, of course, this is not absolutely necessary.

Particular attention is called to the manner 90 in which the thermostatic element is covered or guarded between the base and the extension 11, so that it is practically impossible for the element to be struck by any outside object and so damaged.

95 While I have described my invention and illustrated it in one particular design, I do not wish it understood that I limit myself to this construction, as it is evident that the application of my invention may be varied 100 in many ways within the scope of the following claims.

Claims:

1. In a thermostat the combination, with 105 a thermostatic element and insulation therefor, of a base plate having a tongue extending therefrom and covering said element, and insulation, ears formed from said base plate and clamping said tongue, said insulation and said element together, and an extension of said tongue beyond said clamping point carrying a contact co-acting with a contact carried by said thermostatic element. 110

2. In a thermostat the combination, with a thermostatic element and insulation therefor, of a base plate having a tongue extending therefrom and covering said element and 5 insulation, ears formed from said base plate and clamping said tongue, said insulation and said element together, an extension of said tongue beyond said clamping point carrying a contact co-acting with a contact 10 carried by said thermostatic element, and positioning ears upon said tongue and extending on each side of said clamping ears.
3. In a thermostat the combination, with a thermostatic element and insulation there- 15 for, of a base plate, a clamping tongue ex- tending from said base plate, means for clamping said element and insulation be- tween said tongue and base plate, an ex- tension from said clamping tongue carry- 20 ing thereon a contact co-acting with a con- tact carried by said element, and adjustment means for varying the position of said ex- tension with respect to said base plate.
4. In a thermostat the combination, with 25 a thermostatic element and insulation therefor, of a base plate having a tongue extend- ing therefrom, means formed around and
- clamping said element, insulation and tongue, an extension from said tongue car- 30 rying a contact co-acting with a contact carried by said element, a lip formed up- wardly from said base plate and serving as a stop for said extension, and adjustable means for varying the position of said ex- 35 tension with respect to said lip.
5. In a thermostat the combination, with a thermostatic element carrying a contact point on one end thereof, insulation for said element, a base plate having a tongue ex- 40 tending therefrom and formed around and clamping to said base plate, said element and insulation, clamping ears formed up- wardly from said base plate and locking over said clamping tongue, an extension of said tongue carrying a contact point to co- 45 act with said contact carried by said ele- ment, an upwardly formed lip on said base plate to limit the downward motion of said extension, a dial having a screw extending therefrom engaging by screw connection 50 with said extension and journaled in said base to provide screw adjustment means between said extension and said lip.

EVEN J. ROHNE.
